United States Patent Office

Des. 182,679
Patented Apr. 29, 1958

182,679

FRUIT AND VEGETABLE CHOPPING TRAY OR SIMILAR ARTICLE

Samuel L. McNair, Whitman, Mass.

Application May 9, 1957, Serial No. 46,091

Term of patent 14 years

(Cl. D44—10)

Fig. 1.

Fig. 2.

Fig. 3.

Fig. 4.

Fig. 1 is a top plan view of a fruit and vegetable chopping tray, or similar article, showing my new design.

Fig. 2 is a side elevational view,

Fig. 3 is an end elevational view, and

Fig. 4 is another end elevational view thereof.

I claim:

The ornamental design for a fruit and vegetable chopping tray or similar article, substantially as shown.
